UNITED STATES PATENT OFFICE.

LOGAN R. MOORE, OF SALTSBURG, PENNSYLVANIA.

VESSEL.

SPECIFICATION forming part of Letters Patent No. 783,795, dated February 28, 1905.

Application filed April 4, 1904. Serial No. 201,446.

To all whom it may concern:

Be it known that I, LOGAN R. MOORE, a citizen of the United States of America, residing at Saltsburg, in the county of Indiana and State of Pennsylvania, have invented certain new and useful Improvements in Vessels, of which the following is a specification, reference being had therein to the accompanying drawings.

10 This invention has relation to vessels, measures, and like articles, and has for its object the provision of novel means for preventing the fluid from running down the side of the vessel while pouring liquid from the same and 15 for preventing the dripping of fluid from the edge or lip of the vessel after a quantity has been poured out.

In carrying my invention into effect I provide a vessel of any character adapted to contain liquids with a ledge or flange which I arrange under the upper edge of the vessel or under the lip or pouring-spout of the same, when the same is formed with such ledge or pouring-spout, and the said ledge or flange 25 may entirely surround the vessel or partly surround the same, it being only necessary to locate it at such position that it will prevent the liquid from running down the side of the vessel and receive the drip from that part of the vessel 30 from which its contents are poured. In the case of a bucket, for instance, I form the ledge or flange in two sections, extending each from the bail-ear on one side of the bucket to the bail-ear on the other side of the same, and in 35 the case of a measure or a similar vessel having a pouring lip or spout I locate the ledge below the spout only.

My invention consists in the novel construction, combination, and arrangement of parts 40 to be hereinafter more fully described and claimed.

In the accompanying drawings, Figure 1 is a side elevation of a bucket having my improvements applied thereto. Fig. 2 is a top 45 plan view of the same.

The vessel 1 (shown in Figs. 1 and 2) is an

ordinary metallic bucket and is provided with the usual bail-ears 2 2, the bail 3, and the handle 4. Beneath the upper edge of the vessel 1 I arrange two semicircular flanges or ledges 50 5 5, each ledge extending from near the bail-ear 2 on one side of the vessel to near the bail-ear 2 on the other side, these flanges being preferably flat horizontally-disposed plates and being suitably secured in position by soldering, riveting, or other proper means. 55

In operation the vessels to which my improvement is applied are used in the ordinary manner, and if the fluid starts running down the side it will strike the ledge or flange and be directed in the proper course, and after 60 any fluid has been poured from the vessel and the vessel is restored to the upright position that portion of the fluid which adheres to the edge of the vessel or to the pouring-lip, when 65 the vessel is formed with such lip, will fall upon the ledge, and although the ledge may be flat on top it will receive and hold a considerable amount of fluid and will prevent the same from falling upon the floor or other surface upon which the vessel rests. When the drip has been caught by the ledge or flange, 70 it is either allowed to evaporate or it is wiped off with a cloth.

Having fully described my invention, what 75 I claim as new, and desire to secure by Letters Patent, is—

The combination with a vessel having a lip at its edge, bails on each side, and a handle attached to said bails, of a ledge attached to 80 the vessel immediately below the lip and extending around the vessel, said ledge being cut away on both sides to accommodate said ears, and the said ledge extending farther beyond the sides of the vessel than the said lip. 85

In testimony whereof I affix my signature in the presence of two witnesses.

LOGAN R. MOORE.
